UNITED STATES PATENT OFFICE.

JOHN J. HOLSHUH, OF BROOKLYN, NEW YORK.

DESIGN FOR A COMBINED REFLECTOR AND SUPPORT THEREFOR.

Application filed January 11, 1927. Serial No. 20,330. Term of patent 3½ years.

To all whom it may concern:

Be it known that I, JOHN J. HOLSHUH, a citizen of the United States, residing at Brooklyn, in the county of Kings and State of New York, have invented a new, original, and ornamental Design for a Combined Reflector and Support Therefor, of which the following is a specification, reference being had to the accompanying drawing, forming part thereof.

Fig. 1 is side view of a combined re-

flector and support therefor showing my new design.

Fig. 2 is an end view thereof.

I claim:

The ornamental design for a combined reflector and support therefor as shown.

In testimony whereof I have hereunto set my hand on this seventh day of January A. D., 1927.

JOHN J. HOLSHUH.
